BURIAL BOX

Wilbert W. Haase, Forest Park, Ill., assignor to
 Wilbert Manufacturers Association, Forest
 Park, Ill., a corporation of Illinois

Application September 28, 1945, Serial No. 619,124

1 Claim. (Cl. 72—7)

1 This invention relates to a sectional burial box. It has long been common practice to employ wooden boxes as burial boxes or so-called rough boxes, but the shortage of lumber for making these boxes in recent times has presented manufacturers with the problem of providing satisfactory burial boxes of other materials. One material which suggests itself for this purpose is ordinary sand and gravel concrete but the prohibitive weight of sand and gravel concrete makes it impossible to construct a burial box of such material if the walls of the base or body of the box or the cover are made of single unitary structures. Thus it will readily be appreciated that the weight of the base or body of such a box and the weight of the cover thereof would be far in excess of that which one man could handle and lift at and into a grave opening. However, I have found that a burial box may be advantageously made in part of sand and gravel concrete following the design and construction of the sectional burial box which forms the subject matter of the present invention.

Accordingly, an object of the present invention is to provide a sectional burial box made in part from sand and gravel concrete and in part from other composition materials and so constructed and arranged that each of the component parts thereof may be readily handled by a single man and so that the component parts of the box may be assembled in a grave opening without the necessity for handling prohibitive weights.

An additional object of the invention is to construct the new sectional burial box in such a manner that it possesses relatively great structural strength and resistance to crushing forces to which burial boxes are subjected in grave openings after the grave opening has been filled.

An additional object of the invention is to construct the new sectional burial box in such a manner that it is not dependent on the weight or pressure of the earth in the grave opening to hold the parts thereof together in assembled relationship.

A further object of the invention is to construct the new sectional burial box in such a manner that the component parts thereof are securely held together in assembled relationship without the use of any bolts, screws or other like fastening devices.

Other and further objects of the present invention will be apparent from the following description and claims and are illustrated in the accompanying drawing which, by way of illustra-

tion, shows a preferred embodiment and the principles thereof and what I now consider to be the best mode in which I have contemplated applying those principles. Other embodiments of the invention embodying the same or equivalent principles may be used and structural changes may be made as desired by those skilled in the art without departing from the present invention and the purview of the appended claims.

10 In the drawing,

Fig. 1 is a side elevational view of a typical embodiment of the new sectional burial box showing a portion thereof broken away better to illustrate the construction of the same;

15 Fig. 2 is a top plan view of the body or base of the new burial box, the top thereof being removed;

Fig. 3 is a transverse sectional view of line 3—3 in Fig. 1; and

20 Fig. 4 is a sectional detail view illustrating a feature of the invention.

A typical embodiment of the invention is illustrated in the drawing and comprises a sectional burial box generally indicated at **10**. The new sectional burial box **10** includes a pair of unitary side walls **11** which are relatively thin and light in construction and are preferably composed of asbestos concrete or other suitable material suitably pressed and formed into a single slab or sheet.

The new sectional burial box **10** also includes a pair of end walls **12** which are composed of sand and gravel concrete formed into slabs of the proper size and thickness.

35 The new sectional burial box **10** also includes a sectional bottom wall **13** and a sectional top wall **14**. The sectional bottom wall **13** is composed of a plurality of slabs **13a**, which are preferably made of a suitable quality or type of sand and gravel concrete, and are shown as being four in number. Similarly, the sectional top wall **14** is preferably composed of a plurality of slabs **14a** of sand and gravel concrete which are shown as being four in number. It will be understood,

40 however, that the number of slabs embodied in the sectional bottom wall **13a** and in the sectional top wall **14** is dependent upon the desired length of the box. Thus, while four slabs form a box of average length, it may be desirable and necessary to employ one or more additional slabs in longer boxes.

As shown in the drawing, the lower end portion **11a** of each of the side walls **11** extends into a groove **15** which is formed in the upper surface **55** of each of the bottom slabs or sections **13a** and

the upper end portion 11b of each side wall 11 projects slightly above the upper edges 16 of the end walls 12 and into a corresponding groove 17 formed in the under surface of each of the top wall slabs or sections 14a.

Similarly, the end edges 11c of the side walls 11 project into vertically extending grooves 18 which are formed in the end walls 12, on the inner sides thereof, as shown in Fig. 2.

As best shown in Fig. 4, each of the grooves 15 has a vertically extending or straight inner side wall 19 and an angularly formed outer side wall 20 and the other grooves 17 and 18 are similarly formed for a reason which will be made apparent presently.

In assembling the new sectional burial box the concrete slabs 13a and 14a of the top and bottom walls 13 and 14, respectively, may be formed of sand and gravel concrete, of suitable quality and thickness, with the grooves 15 and 17 formed therein during the forming or molding operation. Similarly, the end walls 12 may be formed of sand and gravel concrete of suitable quality and thickness with the grooves 18 formed therein as shown during the forming operation.

In assembling the new sectional burial box, the bottom slabs or sections 13a will be laid end to end in the bottom of the grave opening and the relatively light side walls 11 will then be inserted in upright position with their lower edge portions 11a projecting into the grooves 15 which are formed in the upper surface of the bottom wall slabs or sections 13a. The end wall sections 12 will then be arranged in upright position on the end bottom slabs 13a with the end portions 11c of the side walls 11 projecting into the grooves 18 which are formed in the inner surfaces of the end walls 12.

After the casket has been lowered into the base of the sectional box thus formed, the top slabs 14a will then be laid upon the base of the box in end to end relation with the upper edge portions 11b of the side walls 11 projecting into the grooves 17 which are formed in the lower surfaces of the top wall slabs or sections 14a, as shown.

It will be noted that each of the grooves 15, 17 and 18 has a straight or vertically extending inside wall 19 and an angled outside wall 20 which extends at an acute angle to the vertically extending inside wall so that the pressure of the earth against the side walls 11 forces those portions of the side walls which are disposed in the grooves 15, 17 and 18 into close contact with the vertically extending straight inside walls 19 of the grooves, thereby forming a tight or close seal therewith. The angled outer side walls of the grooves 15, 17 and 18 facilitate the insertion of portions of the side walls into the grooves and into close fitting engagement with the straight inner side walls 19 of the grooves.

It will thus be seen from the foregoing description, considered in conjunction with the accompanying drawing that the present invention provides a new and improved sectional burial box composed of relatively thin, strong and unitary but light side wall sections, unitary end walls, and sectional top and bottom walls made of sand and gravel concrete but of such size and weight that they may be readily lifted and handled by a single man so as to make it possible to assemble the new sectional burial box in a grave opening.

Moreover, it will also be seen from the fore-

going description that the component parts of the new sectional burial box are held together in assembled relationship without the use of any bolts, screws or like fastening devices, and without reliance upon the pressure or weight of the earth in the grave opening as in the case of certain prior art sectional burial boxes. This is an important feature of the new sectional burial box since it has been found that certain of the prior art sectional burial boxes, which rely upon pressure of the earth in the grave opening to hold the parts thereof together in assembled relationship, collapse and fall apart if an adjoining grave is opened.

It will also thus be seen from the foregoing description, considered in conjunction with the accompanying drawing, that the present invention provides a new and improved sectional burial box having the desirable advantages and characteristics, and accomplishing its intended objects, including those hereinbefore pointed out and others which are inherent in the invention.

I claim:

1. A sectional burial box comprising a plurality of similarly formed cementitious base sections aligned with each other in abutting relationship, each section having a transverse groove formed therein adjacent the free marginal edges thereof, the grooves of the aligned sections being in alignment with one another and constituting a spaced pair of continuous side wall receiving grooves, each groove having a vertically disposed inner wall, a flat base surface of a width corresponding to the width of the edge of a side wall to be received therein, and an angularly disposed outer surface defining a space between the outer surface of the side wall housed in the groove, a pair of relatively light weight one-piece side wall sections, each corresponding substantially in length to the total length of the base, said sections being disposed vertically in the said grooves in the base with the inner wall of each section abutting the inner wall of each groove, a pair of opposite end walls having internal vertical grooves complementary in shape to the first mentioned grooves adjacent the opposite side edges thereof, the respective ends of the side walls being received within the grooves of the respective end walls, and a sectional top comprising a plurality of similarly formed sections each having a groove adjacent the opposite edges corresponding in shape to the first mentioned grooves, said top sections being disposed upon the side wall sections with the grooves in the top receiving the upper edges of the side wall sections, each of the component elements of the box being of such weight that a single workman may handle the same and the angularly disposed surface of each groove facilitating ready assembly of the component sections.
